US0D1063266S

(12) **United States Design Patent** (10) **Patent No.:** **US D1,063,266 S**
(45) **Date of Patent:** **** Feb. 18, 2025**

(54) **ROBOTIC POOL CLEANER**

(71) Applicant: **Maytronics Ltd.**, Kibbutz Yizrael (IL)

(72) Inventors: **Amit Avigdor**, Kibutz Bahan (IL);
Yarden Bashevkin, Tel-Aviv (IL);
Oded Gov, Tel-Aviv (IL)

(73) Assignee: **Maytronics Ltd.**, Kibbutz Yizrael (IL)

(**) Term: **15 Years**

(21) Appl. No.: **35/517,963**

(22) Filed: **Aug. 2, 2022**

(80) **Hague Agreement Data**

Int. Filing Date: **Aug. 2, 2022**

Int. Reg. No.: **DM/223407**

Int. Reg. Date: **Aug. 2, 2022**

Int. Reg. Pub. Date: **Aug. 4, 2023**

(30) **Foreign Application Priority Data**

(57) **CLAIM**

The ornamental design for a robotic pool cleaner as shown and described.

DESCRIPTION

1. Robotic pool cleaner

1.1: Front

1.2: Back

1.3: Top

1.4: Bottom

1.5 : Left

1.6: Right

1.7: Front perspective

1.8 : Back perspective

1.9 : Bottom perspective

The broken lines showing portions of the robotic pool cleaner in the drawings form no part of the claimed design.
